PHONOGRAPH VIEWER CABINET

Richard E. Lee, Cazenovia, N.Y., and Kurt F. Mizen,
Chicago, Ill., assignors to General Electric Company,
a corporation of New York

Filed July 1, 1965, Ser. No. 85,982

Term of patent 14 years

(Cl. D56—4)

FIG. 1 is a perspective view of a phonograph viewer cabinet showing our new design with the phonograph record turntable portion in the tilted-up position;

FIG. 2 is a perspective view with the phonograph record turntable portion in the tilted-down position;

FIG. 3 is a side elevation view, the side not shown being substantially the same in appearance;

FIG. 4 is a front elevation view; and

FIG. 5 is a back elevation view.

In FIGURES 1, 2 and 4 the diagonal lines indicate that the viewing screen on which they appear is a transparent material having a diffusing coating provided thereon to allow rear projection of an image on the screen.

We claim:

The ornamental design for a phonograph viewer cabinet, substantially as shown and described.
